United States Patent Office

Des. 209,291
Patented Nov. 21, 1967

209,291

HEARING AID

Robert L. Geib, Wayzata, Minn., assignor to Dahlberg Electronics, Inc., Minneapolis, Minn., a corporation of Minnesota

Filed July 21, 1966, Ser. No. 3,170

Term of patent 14 years

(Cl. D26—14)

FIG. 1

FIG. 2

FIG. 3

FIG. 4

FIG. 5

FIG. 1 is a side elevational view of a hearing aid showing my new design, the opposite side being substantially a mirror image;

FIG. 2 is an end elevational view thereof as seen from left of FIG. 1;

FIG. 3 is a top plan view thereof;

FIG. 4 is an opposite end elevational view thereof as seen from right of FIG. 1; and

FIG. 5 is a bottom plan view thereof.

The dominant features of my design reside in the portions shown in full lines.

I claim:

The ornamental design for a hearing aid, as shown and described.
